FIG. 1

FIG. 2

FIG. 3

FIG. 4

FIG. 6

FIG. 1 is a front elevational view showing my design for a slide head tool base;

FIG. 2 is a view of the tool base shown in FIG. 1, looking at the tool base of FIG. 1 from the right;

FIG. 3 is an elevational view of the tool base shown in FIG. 1, looking at the tool base of FIG. 1 from the left;

FIG. 4 is a back elevational view of the tool base shown in FIG. 1 and looking at the tool base of FIG. 2 from the right;

FIG. 5 is a top plan view of the tool base shown in FIG. 1; and

FIG. 6 is a bottom plan view of the tool base shown in FIG. 1.

The dominant features of my design reside in the portions shown in full lines; the broken line disclosure of the mounting element is shown for illustrative purposes only.

I claim:

The ornamental design for a tool base, substantially as shown and described.
